UNITED STATES PATENT OFFICE.

DONALD FRASER, OF MILWAUKEE, WISCONSIN, ASSIGNOR TO CHAIN BELT COMPANY, OF MILWAUKEE, WISCONSIN, A CORPORATION OF WISCONSIN.

CONVEYING AND DISTRIBUTING APPARATUS.

1,290,537.

Specification of Letters Patent.

Patented Jan. 7, 1919.

Application filed May 20, 1915. Serial No. 29,391.

To all whom it may concern:

Be it known that I, DONALD FRASER, a citizen of the United States, residing at Milwaukee, in the county of Milwaukee and State of Wisconsin, have invented certain new and useful Improvements in Conveying and Distributing Apparatus, of which the following is a specification.

My invention relates to conveying and distributing apparatus and has for its object to produce means for controlling the discharge of a conveying receptacle that is adapted to traverse an overhead support, it being particularly adapted for use in connection with a bottom-discharging conveying bucket for receiving the product of a concrete mixing machine and delivering it to the desired place of use and there discharging it. The invention, however, is not limited in its useful applications to the one use here specified.

In the accompanying drawings—

Figure 1 is a side elevation of sufficient parts of a concrete mixing and distributing apparatus provided with my invention to illustrate the latter.

Fig. 2 is a cross sectional view taken on the line $\alpha-\alpha$ of Fig. 1.

Fig. 3 is a view, in side elevation, illustrating another embodiment of the invention.

In the drawings 2 indicates a portion of a concrete mixing machine of the rotary drum type, and 3, the framework located near the discharge end thereof. 4 is a bracket supported by the framework in which is mounted the vertical pivot, 5, of a horizontally adjustable boom 6 that constitutes a track or way along which travels a carriage 7 from which is suspended a conveying receptacle 8. The latter is preferably in the form of a bucket of the bottom discharge type, being provided for this purpose with a pair of hinged doors 9. These are arranged to open downwardly and to them are connected links or chains 10 that are in turn connected with the lower end of a curved locking link 11 the upper end of which is pivoted to an arm 12 rigidly secured to an axle or cross shaft 13 suitably mounted, as in the carriage 7. A handle 14 is secured to the shaft 13 and serves as a

means by which the doors may be opened and closed manually, and in the present instance is typical of any means, whether manually or automatically controlled, for closing the doors of the bucket. Automatic means for this purpose are now so well known that they need only to be referred to to be understood. The arrangement for controlling the operation of the doors thus far described is one well known in the art, being disclosed and claimed in U. S. Patent No. 605,620 to Alfred M. Acklin, and constitutes a toggle lock that holds the doors securely closed, but is easily tripped and broken at will, allowing the doors to open by their weight and that of the load which they sustain when the break of the lock occurs.

A cable 15 is connected with the carriage 70 for causing its traverse along the boom 6. I have not thought it necessary to disclose the means for driving this cable, as such means are well known in the art. Suffice it to say that they are motor driven and under the control of an attendant having charge of the operation of the apparatus. The parts thus far described are not novel with me, and therefore not claimed herein.

In order that the bucket may be discharged at any desired place in its line of travel, and that such discharge may be under the control of the attendant, I have devised a mechanism that I will now describe. 80 16 is an arm mounted upon the cross shaft 85 13 and extending upward, preferably alongside the boom 6. As represented in Fig. 1, the upper end of this arm is connected with a free running cable 17. Such cable is in the form of an endless loop supported upon 90 pulleys 18 suitably mounted near the respective ends of the boom. As represented it passes through a perforation in the end of the arm 16, and has stops 19 secured fast to it, one on either side of the arm, so as to insure that the cable shall be moved whenever the carriage and conveying bucket move.

The arm is loosely mounted upon the shaft 13 but is prevented from free rotation in one direction beyond a certain limit, by a stop 20 carried by the lock link 11 with which the arm engages, and from free rotation in the other direction beyond a certain limit, by a stop 25 carried by the frame

of the carriage 7. The result of this arrangement is that if the arm be turned about its axis of support in the direction of the arrow *a* in Fig. 1, it will cause a partial 5 rotation of the shaft 13; and with this shaft will turn the arm 12 to which the upper end of the lock link 11 is pivoted. As soon as the arm 12 is turned a short distance the toggle lock already referred to and that 10 serves to hold closed the doors of the receptacle 8 becomes broken and then the doors open, as has been described. In turning to the discharging position here indicated, the shaft rotates independently of the arm 16, 15 which is held from following the other parts in their rotative movements by the cable 17. In order to move the arm 16 and cause a sufficient rotation of the shaft 13 to break the toggle lock for the doors of the 20 bucket 8, I employ means for arresting the free movement of the cable 17, and, as shown, such means consist of a brake 21 arranged to bear upon one of the pulleys 18 about which the cable 17 passes, and manually 25 controlled means for operating the brake. The brake 21 preferably bears against the pulley located near the inner or pivoted end of the boom, and the means for operating it consist of a handle 24, preferably of bell crank form, a connecting link 23 extending axially through the vertical pivotal support for the boom, and a lever 22, this arrangement permitting the brake to be operated no matter what be the angle 30 to which the boom may be set.

It will be understood that the cable runs very freely so that it is moved by the arm 16 whenever the bucket and its carriage are caused to traverse the boom, the drag of the 35 cable upon the arm 16 when it is left free to run, being insufficient to cause the breaking of the lock that holds the bucket in charge-receiving condition.

The operation of the apparatus may now 40 be described. The bucket is brought back to the inner end of the boom to receive a charge from the mixing machine. Either manually or by automatically operating means the doors 9 are closed and locked. 45 After the bucket receives its load it is run out along the boom by the cable 15, and as it moves the arm 16 travels with it and moves the cable 17, pulling the part to which it is connected along with it. As the 50 bucket reaches the place when its load is to be discharged the operator applies the brake 21, and thereby arrests the movement of the cable, while the bucket and its carriage are still advancing, with the result that the 55 arm 16 is rocked, in the direction of the arrow *a*. This, as has been described, causes a tripping of the toggle lock of the doors of the bucket, which thereupon open, allowing the load to be discharged. Before the 60 bucket is returned to loading position the 65

brake 21 is released, and as soon as the carriage begins to move inwardly the arm 16 moves into position bearing against the stop 25 by which it is arrested in its normal position, the cable 17, or the part thereof to 70 which the arm is connected, following the arm on its return movement.

In Fig. 3 I have illustrated an arrangement slightly different from that described. Here the cable 17' instead of being an endless loop supported upon a pair of pulleys 18, has one end secured to the upper end of the arm 16 and its other end secured to a spring-controlled winding drum 26. Upon this drum bears a brake 21 like that already 75 described. In operating with this form of my invention the cable 17 is drawn off from the drum as the bucket and carriage move outward along the boom. The tripping of the toggle lock is effected as in the other 80 case by arresting the movement of the cable. When the parts are returned toward the inner end of the boom the spring 27 connected with the drum 26 rotates the latter in a direction to wind up the cable, as will be 85 understood.

It is evident that the cable is a device for operating a lock that maintains the conveying receptacle in load-receiving condition, and is movable freely back and forth 90 with the said receptacle; and that the brake is a mechanical means for arresting the movement of the said freely moving, locking operating device, so as to cause the lock to be operated to permit the receptacle to discharge; and my invention includes these 95 features whether embodied in the specific arrangements shown or in other variations, modifications or equivalent forms thereof.

What I claim is:—

1. The combination of a supporting framework, a track extending therefrom, a carriage supported on the track, a conveying bucket suspended from the carriage, locking means for maintaining the bucket in load-receiving condition, means for causing the traversing of the carriage and bucket along the track, an arm pivotally supported on the carriage and free to have a limited rocking movement, and adapted when 100 rocked to act on the locking means to release the bucket for discharge, a cable connected with the said arm and movable therewith, and means under the control of the operator for arresting the movement of said cable whereby the arm is caused to be rocked and to operate the locking means.

2. The combination of a supporting framework, a track extending therefrom, a carriage movable along the track, power driven 105 means connected with the carriage for moving it along the track, a conveying bucket suspended from the carriage having bottom closing doors, a toggle lock supported on the carriage and connected with the doors, hold-

ing them closed, an arm pivoted in the carriage and arranged to act upon the toggle lock to break it and permit the doors to open, a cable connected with the arm near 5 its free end and freely movable therewith as the carriage traverses the track, and means under the control of the operator for ar-

resting the movement of the cable at will whereby the arm is rocked to break the toggle lock.

DONALD FRASER.
